UNITED STATES PATENT OFFICE

2,496,376

INTERRUPTER

Le Roy A. Cleaveland, Mountainside, and Frank H. Tooker, West Orange, N. J., assignors to United States Instrument Corporation, Summit, N. J., a corporation of New Jersey

Application September 3, 1947, Serial No. 771,876

7 Claims. (Cl. 172—126)

1

This invention relates to current interrupters for electrical circuits and more particularly to a current interrupter of extremely low power, for use in a circuit containing a vibrator, such as a telephone receiver for example, adapted to give off an audible signal when fed by an interrupted current of a frequency within the audible range. Such a device may be particularly useful when employed in the calling circuit of a so-called "sound-powered" telephone, the receiver of which is adapted to emit a clearly audible signal when fed with an interrupted current of only two or three milliamperes. The energy source may be an ordinary dry cell of one and one-half volts.

One object of the present invention is the provision of an interrupter of the type described in which the armature is dynamically balanced and supported by spring means, whereby the device may be mounted in any position without affecting its operation, and a minimum gap may be employed between armature and pole-piece, thus permitting the use of a minimum of energy.

Another object is the provision of such a device in which the spring armature support has an extension bearing upon but insulated from a contact post which also carries the fixed contact member, whereby the position of the armature may be varied by deforming one end of said contact post, while the position of the fixed contact may be varied by deforming the other end of said contact post. By virtue of these features, which permit of the use of very little energy for operation, the device may also be made extremely small and compact.

Other and further objects, features and advantages will be apparent from the description which follows, read in connection with the accompanying drawings in which:

Figure 1 is a vertical sectional view of a device constructed according to the invention;

Figure 2 is a rear end view of the device of Figure 1;

Figure 3 is a horizontal section on line 3—3 of Figure 1;

Figure 4 is a front end view of the device;

Figure 5 is similar to Figure 1, but shows a modified form of the invention;

Figure 6 is a top plan view of the said modified device; and

Figure 7 is a horizontal section on line 7—7 of Figure 6.

In order to facilitate an understanding of the invention, reference is made to the embodiments thereof shown in the accompanying drawings and detailed descriptive language is employed. It 55

2

will nevertheless be understood that no limitation of the invention is thereby intended and that various changes and alterations are contemplated such as would ordinarily occur to one skilled in the art to which the invention relates.

Referring now to Figures 1 to 4, inclusive, the device there illustrated comprises a substantially U-shaped pole-piece 10 one leg 11 of which is surrounded by and forms a core for the coil 12 of fine wire, an armature 13 supported with its midpoint substantially opposite the end of the other leg 14 of the pole-piece by means of a leaf-spring 15 which also carries a contact 16, and a contact post 17 which carries a fixed contact 18. The armature 13 may rest upon or be slightly spaced from the pole-piece leg 14 while an end of the armature is normally spaced somewhat from the leg 11. The device is completed by terminal members 19, 20 and 24, suitably insulated from each other, the entire assemblage being secured together by screws 22, which also serve to electrically connect terminal member 19 and spring 15.

The electrical circuit involved is well known and need not be described in detail except to note that the contacts 16 and 18 are in series with the coil 12, both contacts and coil being connected between the poles of a suitable energy source. An interrupted current may be taken off either across the contacts 16, 18 or across the coil 12, and fed to the telephone receiver or other audible signalling device.

The form of spring 15 is best seen in Figures 1 and 3, and comprises a bifurcated vertical portion 15c which is secured between the pole-piece leg 14 and the vertical bifurcated portion 17a of the contact post 17, being insulated from the latter. The horizontal portion of the spring 15 terminates in an apex 15a which carries the movable contact 16, while a rearwardly extending tongue 15b carries the armature 13. Adjustment of the air gap between armature and pole-piece, and of the distance between the contacts, is secured by bending the spring 15, the contact post 17, or both.

The device of Figures 5 to 7 is similar to that of Figures 1 to 4 except that in this instance the spring 25 is formed with a rearward extension 26 which not only supports the armature 27 but continues rearwardly and upwardly to bear against a rearward extension 28 of the contact post 29, being insulated therefrom as at 30. In this case the spacing of the contacts is regulated by bending the forward end of the post 29, while the position of the armature is controlled by

bending the rearward extension 28 of the post 29.

In either form of the invention, the air gap and contact spacing may be very minutely regulated, thereby permitting the device to operate with a minimum of power, and likewise the armature is dynamically balanced, the gravity effects being eliminated so that the device may be used in any position.

Having thus described the invention, what is claimed as new and desired to be secured by Letters Patent is:

1. In a current interrupter for electrical circuits, a U-shaped pole-piece forming part of a magnetic circuit, an armature adapted to complete said circuit, a coil surrounding one leg of said pole-piece, and means for rapidly interrupting the current through said coil, said last means comprising a pair of contacts in series with said coil, one of said contacts being fixed and the other movable with said armature, a contact post, said fixed contact being secured on said contact post and said contact post being deformable to vary the normal distance between said contacts, and spring means rigid with said pole-piece for suspending said armature with its midpoint opposite the other leg of said pole-piece.

2. In a current interrupter for electrical circuits, a U-shaped pole-piece forming part of a magnetic circuit, an armature adapted to complete said circuit, a coil surrounding one leg of said pole-piece, and means for rapidly interrupting the current through said coil, said last means comprising a pair of contacts in series with said coil, one of said contacts being fixed and the other movable with said armature, a contact post, said fixed contact being secured on said contact post, and spring means rigid with said pole-piece for suspending said armature with its midpoint opposite the other leg of said pole-piece.

3. In a current interrupter for electrical circuits, a U-shaped pole-piece forming part of a magnetic circuit, an armature adapted to complete said circuit, a coil surrounding one leg of said pole-piece, and means for rapidly interrupting the current through said coil, said last means comprising a pair of contacts in series with said coil, one of said contacts being fixed and the other movable with said armature, a contact post, said fixed contact being secured on said contact post, and spring means rigid with said pole-piece for suspending said armature with its midpoint opposite the other leg of said pole-piece, said spring means also carrying said movable contact.

4. In a current interrupter for electrical circuits, a U-shaped pole-piece forming part of a magnetic circuit, an armature adapted to complete said circuit, a coil surrounding one leg of

said pole-piece, and means for rapidly interrupting the current through said coil, said last means comprising a pair of contacts in series with said coil, one of said contacts being fixed and the other movable with said armature, a contact post, said fixed contact being secured on said contact post, and spring means rigid with said pole-piece for suspending said armature with its midpoint opposite the other leg of said pole-piece, said spring means having an extension bearing against said contact post and said contact post being deformable to vary the position of said armature through said spring.

5. In a current interrupter, a contact post, a substantially U-shaped pole-piece, a coil surrounding a leg of said pole-piece, a pair of contacts in series with said coil, an armature having its midpoint located substantially over the other leg of said pole-piece, and spring means supported on said pole-piece and supporting said armature and one of said contacts, said other contact being secured on said contact post.

6. In a current interrupter, a contact post, a substantially U-shaped pole-piece, a coil surrounding a leg of said pole-piece, a pair of contacts in series with said coil, an armature having its midpoint located substantially over the other leg of said pole-piece, and spring means supported on said pole-piece and supporting said armature and one of said contacts, said other contact being secured on said contact post, said contact post being deformable to vary the normal distance between said contacts.

7. In a current interrupter, a contact post, a substantially U-shaped pole-piece, a coil surrounding a leg of said pole-piece, a pair of contacts in series with said coil, an armature having its midpoint located substantially over the other leg of said pole-piece, and spring means supported on said pole-piece and supporting said armature and one of said contacts, said other contact being secured on said contact post, said spring means acting between said contact post and said armature to control the position of the latter.
